CLAIM

The ornamental design for an electronic device holder as shown and described.

DESCRIPTION

FIG. 1 is a top, front, right perspective view of an electronic device holder, shown in a first configuration;

FIG. 2 is a top, rear, left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top, front, right perspective view of the electronic device holder of FIG. 1, shown in a second configuration; and,

FIG. 10 is a top, front, right perspective view of the electronic device holder of FIG. 1, shown in a third configuration.

The dash-dash broken lines in the drawings depict portions of the electronic device holder that form no part of the claimed design.

1 Claim, 10 Drawing Sheets
